UNITED STATES PATENT OFFICE.

GEORGE M. BACON, OF SALT LAKE CITY, UTAH.

ROTARY VALVE.

1,309,059.

Specification of Letters Patent. Patented July 8, 1919.

Application filed March 16, 1917. Serial No. 155,369.

To all whom it may concern:

Be it known that I, GEORGE M. BACON, a citizen of the United States, and a resident of Salt Lake City, in the county of Salt Lake and State of Utah, have invented a certain new and useful Improvement in Rotary Valves, of which the following is a specification.

The present invention relates to valves, and more particularly to that class known as rotary valves particularly adapted for such use as disclosed in co-pending application, Serial Number 149549, filed February 19, 1917 for a centrifugal separator wherein the valves are arranged in the periphery of the drum or casing and are adapted to feed material radially from the drum or casing while the latter is rotated.

An object of the present invention is to provide an improved form of valve wherein is eliminated the frictional contact of machined surfaces, and wherein the valve head or body is packed efficiently in the casing.

It is the further aim of the present invention to provide a valve of this type with a plurality of packing elements which may be independently positioned and removed upon the valve body, and a valve which is so constructed as to provide a plurality of pockets in the peripheral surface thereof to effect a continuous feeding of material or the like through the casing in predetermined quantities.

The above, and various other objects and advantages of this invention will be in part described, and in part understood, from the following detailed description of the present preferred embodiment, the same being illustrated in the accompanying drawing wherein:

Figure 1 is a side elevation of a valve head constructed according to the present invention.

Fig. 2 is a horizontal section through the valve, a portion of the casing therefor being disclosed.

Fig. 3 is a longitudinal section through the valve head taken through a pair of opposed pockets of the valve.

Referring to this drawing, 10 designates an elongated hub portion provided with a fluted peripheral surface the concavities of which extend longitudinally of the hub, and form substantially a polygonal body member. The concavities of the hub 10 thus

formed may be in any desired number, and provide pockets the inner walls of which are transversely concaved and form at their adjacent sides radially extending and outwardly tapering ribs or partition walls 11.

A packing strip 12 is placed longitudinally in each lateral pocket of the hub 10, and may be formed of leather, of the like, which is held to the configuration of the inner wall of the pockets by a shaper or clamping plate 13. Each clamping plate 13, one for each strip 12, is transversely curved and is preferably of a length slightly greater than that of the hub 10. Machine screws 15, or the like, are secured through the curved plates 13, and pass inwardly through the packing strips 12 and into the sides of the hub 10.

The ribs 11 fit between the inner faces of each adjacent pair of packing strips 12, and project the adjacent edge portions of the packing strips outwardly to form partition walls 14 defining the lateral sides of the pockets.

The valve head thus formed is adapted to engage in the opening or way formed in the valve casing or wall 16, and the free edges of the packing strips 12 are adapted to abut flat against the inner surface of the wall 16. As shown in Fig. 2, the partitions or free edge portions 14 of the packing strips fit snug against the inner surface of the wall 16 and seal the pockets or compartments from one another. When the valve is rotated, the pockets are consecutively opened at one side of the wall 16, to receive a charge of material or the like, and are consecutively opened at the opposite side of the wall 16 to consecutively deliver the contents.

From Fig. 3, it will be noted that the packing strips 12 are of a length slightly greater than that of the hub portion 10 for the purpose of freeing the opposite end edges of the packing strips and effect the tight sealing of the hubs in the casing 16. The shapers or retaining plates 13 are also of less length than that of the packing strips 12, and are of less width than the same to admit of the free movement of the end and lateral edges of the packing strips for sealing the hub 10 in the casing 16.

It is apparent that should the material used, injure any one or more of the packing strips 12, the latter may be individually removed from the hub 10 by detaching the ad-

jacent retaining plates or shapers 13. The hub 10 is provided at opposite ends with spindle or journal portions 17 which are of less diameter than that of the hub 10, and 5 which may be of any desired length. The pockets or recesses formed in the opposite sides of the hub 10 may be of any desired size, and when the valve is in operation, the pockets regulate the feeding of material 10 through the casing or wall 16 in predetermined quantities.

It is of course understood that the valve 15 of this invention may be used for various purposes, and that various modifications and changes may be made in the same without departing from the spirit of the invention, and being restricted only by the scope of the following claims.

I claim:—

20 1. In a rotary valve, the combination of a hub provided with recesses in its opposite sides, and packing strips fitted in said recesses and having their lateral edges in contact to furnish sealing and pocket defining elements.

25 2. In a rotary valve, the combination of a hub provided with a recess in and extending the full length of its side and open at the ends of the hub, and a packing strip 30 fitted in said recess against the inner wall thereof and having its opposite edges projecting outwardly from the hub to form sealing and pocket defining elements.

35 3. In a rotary valve, the combination of a hub provided with a fluted peripheral surface, and packing strips fitted to said surface in the concavities thereof and having their lateral edges in contact to provide sealing and pocket defining elements.

40 4. In a rotary valve, the combination of a hub provided with longitudinal concavities in its opposite sides, a plurality of packing strips fitting in said concavities, shapers secured against said packing strips to 45 form the same to the inner walls of the concavities, the adjacent lateral edge portions of said strips being held in abutting relation and extending radially from the hub to provide partition walls defining pockets 50 in the concavities and for sealing the valve.

5. In a rotary valve, the combination of a hub provided with a longitudinally ex-

tending concavity in the side, a packing strip seated in said concavity, a shaper engaging against the outer surface of said packing strip to conform the latter to the curvature of the inner wall of the concavity, said packing strip being of greater length than the hub and extending at opposite ends beyond the hub, said packing strip also having its lateral edges extending outwardly from the hub for sealing the same and to provide pocket-defining elements.

6. In a rotary valve, the combination of a hub provided with longitudinally extending concavities in its opposite sides providing partition ribs between the concavities, packing strips extending longitudinally in the concavities, transversely curved plates fitting against the outer faces of said strips, 65 securing means for the plates engaging the hub for binding the plates against the strips to conform the latter to the inner walls of the concavities, said packing strips extending at their opposite ends beyond the 70 ends of the hub, and said transversely curved plates terminating at opposite ends short of the extremities of the packing strips, said curved plates also terminating at their lateral edges short of the free edges 80 of said packing strips to provide packing elements at opposite sides of the concavities.

7. In a rotary valve, the combination of a casing provided with a substantially cylindrical chamber therein communicating through the opposite sides of the casing, a hub arranged concentrically within the casing and provided with longitudinally extending recesses in its sides, packing strips fitting in said recesses, shapers engaging the packing strips to conform the same to the inner walls of the recesses in the sides of the hub, and securing elements passing inwardly through the shapers and the packing strips and being supported by the hub, said packing strips extending at their lateral edges beyond the shapers and adapted for contact with the inner walls of said casing to seal the valve therein and to define 100 a pocket between the lateral edges of each packing strip.

GEORGE M. BACON.
